Inventor

Albert Brown

By *Watson E. Coleman*
Attorney

UNITED STATES PATENT OFFICE.

ALBERT BROWN, OF VALE, OREGON, ASSIGNOR OF ONE-HALF TO GEORGE W. CLEVINGER, OF VALE, OREGON.

SCREW CASING.

Application filed May 6, 1922. Serial No. 558,957.

To all whom it may concern:

Be it known that ALBERT BROWN, a citizen of the United States, residing at Vale, in the county of Malheur and State of Oregon, has invented certain new and useful improvements in Screw Casings, of which the following is a specification, reference being had to the accompanying drawings.

This invention relates to certain improvements in a screw casing and it is an object of the invention to provide a novel and improved device of this general character which is adapted to be inserted within the work and in which the screw is directly engaged whereby the hole is prevented from rotting and permitting the screw to be removed or applied indefinitely without enlarging the screw hole and to further assure the maintenance of the screw in applied position.

The invention consists in the details of construction and in the combination and arrangement of the several parts of my improved screw casing whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in elevation and partly in section illustrating a screw casing constructed in accordance with an embodiment of my invention and in applied position,

Figure 2 is a view similar to Figure 1 with the casing in elevation, and

Figure 3 is a view in plan showing a blank of which my improved casing may be formed.

My improved casing is formed of a sheet of relatively thin metal rolled to conform to the peripheral configuration of the co-acting screw S, said casing being split from

one end to the other as at 1. By having the casing split or open at one side the same 50 can be readily expanded when applied in the opening in the wood and as the screw is inserted therein.

The casing has pressed or otherwise formed therein the threads 2 coincident with the 55 threads on the screw S.

The casing, as disclosed herein, is of a type particularly adapted for wood screws and especially in connection with furniture, musical instruments, refrigerators or other 60 wood work. The wall defining the screw opening is prevented from rotting by water and the screw S can also be repeatedly removed or applied without ruining the threads or enlarging the screw opening and 65 thereby preventing the screw from working or being pulled out.

The outer end of the casing is defined by a laterally disposed flange 3 which is adapted to fit tightly against the adjacent surface 70 of the wood work when the casing is in applied position.

Struck from or otherwise provided on the casing are the prongs or barbs 4 disposed on an outward incline toward the opening 75 or entrance end of the casing. As the ends expand upon the insertion of a screw S therein the prongs or bars 4 will penetrate the wall defining the screw opening whereby said sleeve is effectively maintained in 80 applied or working position.

From the foregoing description it is thought to be obvious that a screw casing constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in 95 practice except as hereinafter claimed.

I claim:

A sleeve for a screw comprising a sheet of metal bended to conform to the peripheral configuration of the screw, the longitudinal edges of the metal being disconnected to provide a longitudinal slit along one side of the casing to permit the casing to expand upon the insertion of a screw therein, the

inner surface of the casing having threads to receive the threads of the screw, prongs 10 extending outwardly from the casing, and incline in a direction toward the entrance end of the sleeve.

In testimony whereof I hereunto affix my signature.

ALBERT BROWN.
